DESIGN FOR AN ADVERTISING SIGN

Fred Benioff, San Francisco, Calif.

Application March 20, 1940, Serial No. 91,089

Term of patent 7 years

To all whom it may concern:

Be it known that I, Fred Benioff, a citizen of the United States, residing at the city and county of San Francisco, State of California, have invented a new, original, and ornamental Design for an Advertising Sign, of which the following is a specification, reference being had to the accompanying drawing, forming a part thereof in which Fig. 1 is a perspective view of the advertising sign; and Fig. 2 is an edge elevational view thereof, the portion illustrated in dotted lines in Fig. 1 being omitted.

I claim:

The ornamental design for an advertising sign, substantially as shown.

FRED BENIOFF.
